UNITED STATES PATENT OFFICE.

PETER VANDERAUWERA, OF NEW BRUNSWICK, NEW JERSEY, ASSIGNOR TO THE WEBB WIRE WORKS, OF NEW BRUNSWICK, NEW JERSEY, A CORPORATION OF NEW JERSEY.

PLATE-STAND FOR WIRE-DRAWING.

No. 922,979.

Specification of Letters Patent.

Patented May 25, 1909.

Application filed June 30, 1908. Serial No. 441,149.

To all whom it may concern:

Be it known that I, PETER VANDERAUWERA, a subject of the King of Belgium, residing at New Brunswick, in the county 5 of Middlesex and State of New Jersey, have invented certain new and useful Improvements in Plate-Stands for Wire-Drawing, of which the following is a specification.

My invention relates to a plate stand for 10 wire drawing, the object being to provide a stand which will overcome the objectionable features incident to the use of the present fixed stand.

In wire drawing it is customary to use a 15 die plate having numerous holes drilled therein. In practice it is difficult to form and maintain these holes with absolute accuracy; that is, perpendicular to the face of the plate, so that considerable time is required by the operator to "cast" the wire 20 at the beginning of the drawing; that is, to make the drawn wire have a tendency to assume a coil of not less diameter than that of the block. The die plate in general use 25 rests in a stand fixed to the bench and unless the plate is properly aligned the wire becomes what is called "wavy"; that is, tends to go into a coil the diameter of which is less than that of the block. In beginning the drawing 30 of a given reel of wire it is necessary for the operator, after drawing the end through one of the die holes and securing it to the block and starting the rotation of the latter, to manipulate the die plate by 35 hand and by means of wedge blocks so adjust it on the fixed stand that the axis of the die hole will strike the given point on the circumference of the block where every coil or convolution begins. It is only by 40 long experience that an operator is able to align the die plate properly and even then it requires several minutes and the rotation of the block twenty or more times before the proper adjustment can be made. This 45 loss of time is considerable in a mill having a large number of blocks and in addition to this loss of time the initial wavy coils or convolutions of the wire give considerable trouble in the subsequent drawings. In fact, 50 it is often necessary to scrap these wavy coils.

By means of the stand hereafter described I am enabled to align or adjust the die plate before the drawing begins by a very

simple operation requiring but a few seconds 55 of time and by which the first convolution is properly coiled around the block thus avoiding any loss of material. This saving in time and material will be appreciated when it is understood that in some cases as 60 many as ten drawing operations are necessary for piano wire, the class of work to which my invention has been applied in practice, and to begin successive operations with a reel of wire that has been previously 65 properly drawn throughout its length is of great advantage.

The essential feature of my invention comprises a die stand supported in such manner as to be capable of free movement 70 in every direction so that when the die plate is clamped in position before the drawing operation, or before the insertion of a wire through a die hole, the die plate will remain in fixed relation to the stand and requires 75 no subsequent manipulation relatively thereto. In addition to this feature the stand also comprises a guide for the wire capable of adjustment in axial alignment with a given die hole so that upon the insertion of 80 the wire at the beginning of the drawing operation the initial rotation of the block upon which the drawn wire is coiled will swing the stand and the plate and guide carried thereby into such position that 85 the wire will be properly cast. These and other features of the invention will be understood from the following description taken in connection with the accompanying drawings in which—

Figure 1 is a top view of the complete stand; Fig. 2 a vertical longitudinal section on the plane of the line 2—2 of Fig. 1; Fig. 3 a transverse vertical section on the plane of the line 3—3 of Fig. 1 looking in the direction of the arrow; Fig. 4 a rear elevation; and Fig. 5 a detail view of a modification.

Similar numerals of reference indicate similar parts in the several views.

The die plate holder illustrated comprises end pieces 1 and 2 in the form of castings of suitable shape. The former is provided on its inner face with a central recessed boss 1', as indicated in Fig. 2, and its outer face 105 is recessed at three points equidistant from the center of the boss 1'. In practice the end piece 1 is cast in the form of a spider

with three legs, the recesses 4 being formed near the outer ends of the legs. The end piece 2 is formed with a central opening 5 to receive one end of a guide as described hereafter, and with three overhanging brackets or lugs 6 recessed at the points 7 equidistant from the center of the opening 5. The recesses 7 are struck on a circle having the same radius as that on which the recesses 4 in the piece 1 are struck. The pieces 1 and 2 are connected through three straps 8 of equal length, and stirrups 9 secured to the ends of said straps. The stirrups encircle the recessed ends of the forward piece 1 and the overhanging lugs 6 of the piece 2, and are provided with inwardly projecting hardened steel studs 10 which rest in the recesses 4 and 7. The straps 8 extend within the bodies of the stirrups and are of such length as to prevent the unseating of the studs 10. As shown in Fig. 2, there is a slight play between the straps and the end pieces. One purpose being to permit of a universal movement of the stand and die plate, I support the former at one end by an anchor 11 secured to the bench and having its inner end 12 turned and pointed to seat in the recessed hub 3. At its other end the stand is hung upon a bent rod 13 having its inner end 14 turned upwardly to form a pintle which passes through the openings of ears 15 formed on the back of end piece 2, as shown in Fig. 4. Near its outer end rod 13 is held by a bracket 16 beyond which it carries an adjustable weight 17. The anchor 11 and rod 13 are so formed and disposed as to support the stand a short distance above the bench to permit of a universal movement of the stand without coming into contact with the bench.

It will be seen from the above description that the stand is supported freely at both ends and that it is capable of swinging laterally as well as vertically about the pointed anchor 11, the parallelism of the end pieces 1 and 2 being maintained at all times through the straps 8, a transverse section through the latter forming an equilateral triangle.

The die plate 3 is of the usual form, having a series of drilled holes 3', and is adapted to be placed in position to utilize any one of the holes for the drawing operation. It is placed in position with one of the holes opposite the opening 5 in end piece 2 and rigidly retained by a stiff spring plate 18 secured to a bracket 19, preferably in the form of a casting having arms 20 rotatably mounted in ears 20' forming part of the end piece. Secured to or formed integral with the swinging bracket 19 is a conical guide 21 adapted to enter the holes of the die plate on the back or entering face of the latter. Any suitable means may be employed to secure the clamp plate 18 in position. For

that purpose I have shown a spring arm 22 fastened to end piece 2, bent as shown in Fig. 2 and formed at its outer end with ratchet teeth 23 to engage the wall of an opening 24 in the upper end of plate 18. By depressing the free end of arm 22 clamp plate 18 may be swung outwardly to release the die plate. When locked as shown in Fig. 2, the die plate will be rigidly held against any movement relatively to the stand.

In order to properly aline the stand and die plate after the former has been clamped in position I provide a carrier 25 supported freely in one end of a curved arm 26 adapted to be moved vertically between clamp plates 27, and in a horizontal direction through a clamping device 28. The plates 27 are supported on a threaded rod 29, secured to end piece 2, said rod carrying a nut 30 by which the outer plate 27 may be moved to clamp or release arm 26. The clamp 28 is also supported upon end piece 2 and is of known form as shown in Fig. 1. The curved arm 26 is struck on an arc from the center of a given die hole when the die plate is in position, and by the means described the carrier 25 may be adjusted to any desired position so as to be in axial alinement with a given hole of the die plate. As an additional guide for the wire as it emerges from the die plate, I provide a curved arm 31 to which the carrier 25 is rigidly secured, said arm having its inner end of tubular form and resting freely in the opening 5 of end piece 2 and abutting against the front of the die plate, as shown in Fig. 2. The carrier 25 may be placed as far as practicable from the die plate, it being obvious that the farther it is away the more sensitive will be its action on the stand and die plate.

The operation of the device is as follows. The die plate is first placed with one of its holes opposite the opening 5 and then clamped in position by moving plate 18 to cause the guide 21 to enter the back of the hole. Plate 18 is then locked by arm 22. The operator then runs a long straight needle, called a set, through the die hole and the tubular extension of the swinging arm 31. Carrier 25 is then adjusted either vertically or horizontally or both, as may be necessary, to enable the set to pass through it without deflection. When so adjusted, the carrier 25 is clamped securely in place, the result being that the die hole and carrier 25 are in axial alinement. The set is then withdrawn and the end of the reel of wire inserted through the die hole in the usual manner, passing through the tubular extension of arm 31, and carrier 25 to the block where it is fastened. The block is rotated and the drawing proceeded with, the alinement of the die hole and carrier 25 securing the desired position of the die plate to effect the

proper drawing and coiling of the wire at the outset of the operation. Should the axis of the die hole and carrier 25 not be in alinement with a given point on the block when 5 the wire is fastened to the latter, a slight rotation of the block will swing into and maintain the stand in such position that the axis of the die hole will strike a given point on the circumference of the block at which 10 each convolution begins, and such alinement will be maintained during the entire drawing operation. Any deflection of the axis of the die hole is prevented, during the drawing operation, by the wire acting on the 15 carrier 25. I thus dispense with the manipulation of the die plate as now customary with the fixed stand and am enabled to cast the wire properly on the initial rotation of the block.

20 By the use of the present stand the operator has to pay no attention to the position of the die plate relatively to the block; that is, it requires no manipulation of the die plate relatively to the block during the formation 25 of the initial coils on the block. The weight 17 is adjusted on rod 18 to act as a counter-balance for the stand and to relieve the traveling wire of the weight of the stand. The centers of the recessed boss 1' 30 and the opening 5 in end piece 2 lie in the axis of the stand so that free lateral and vertical movements are permitted about the end of anchor 11 to allow of the proper alinement of the die hole and carrier 25 with 35 the block.

In Fig. 5 I have shown a modified form of support for the carrier 25. In this form the guide is suitably supported in a bracket at the ends of two threaded rods 32 placed 40 at right angles to each other and having bearings in a bracket 33 which may be conveniently secured to the end piece 2. The movements of rod 32 to properly aline the guide may be effected by nuts 34 held between the fixed bearings of bracket 33, as 45 will be readily understood.

It is to be understood that various modifications may be made in the details of the construction of the stand herein described 50 so long as the essential features thereof are retained.

What I claim and desire to secure by Letters Patent is:—

1. The combination of a die plate and stand 55 therefor, a support for said stand which permits of its universal adjustment, and means connected to said stand and acted on by the wire to effect the proper alinement of the die plate relatively to the block before beginning the drawing operation.

2. The combination of a die plate and stand therefor, a support for said stand which permits of its universal adjustment, and a carrier for the wire which is acted on 60 by the wire to cause the stand and die plate

to assume a definite position before beginning the drawing operation.

3. The combination of a die plate and stand therefor, a support for said stand which permits of its universal adjustment, 70 and a carrier connected to said stand in such manner as to be acted on by the wire to cause the stand to assume a definite position.

4. The combination of a die plate and stand therefor, a support for said stand 75 which permits of its universal adjustment, and a carrier for the wire, said carrier being connected to the stand and acted on by the wire to effect the proper alinement of the die plate and block before beginning the 80 drawing operation and to maintain a proper alinement during the drawing operation.

5. The combination of a die plate and stand therefor, a support for said stand which permits of its universal adjustment, 85 a carrier supported on the delivery side of the die plate, and means to effect the alinement of said carrier with a given hole of the die plate for the purpose described.

6. The combination of a die plate and stand therefor, a support for said stand which permits of its universal adjustment, 90 means for clamping the die plate in fixed relation to the stand, a carrier for the wire connected to said stand, and means to adjust 95 said carrier both vertically and horizontally and to clamp it in fixed relation to the stand, whereby any movement of the carrier by the wire during the drawing operation will effect a readjustment of the die plate relatively to the block. 100

7. The combination of a die plate and stand therefor, said stand comprising end pieces, straps loosely connected to said end pieces to permit a parallel movement thereof, 105 means to clamp the die plate to one of said pieces, and a support for said stand which permits of its universal adjustment.

8. The combination of a die plate and stand therefor, said stand comprising end 110 pieces, straps loosely connected to said pieces to permit a parallel movement thereof, means to clamp the die plate to one of said pieces, a carrier for the wire connected to said stand, and means to adjust said carrier 115 and to clamp it in axial alinement with a given hole of the die plate.

9. The combination of a die plate and stand therefor, said stand comprising end pieces having recesses at points equidistant 120 from the centers thereof, straps having studs adapted to seat in said recesses thereby connecting said end pieces, and supports connected to said end pieces to permit of universal adjustment of said stand while maintaining the parallelism of the end pieces. 125

10. The combination of a die plate and stand therefor, said stand comprising end pieces one of which has a central recessed boss on one of its faces and recesses in its 130

face at points equidistant from the center of said boss, the other end pieces having a central opening therein and recesses at points equidistant therefrom, straps loosely connected to said pieces to permit of a parallel movement thereof, and supports for said pieces on which the stand is freely suspended.

11. The combination of a die-plate and stand therefor, said stand comprising end pieces, straps loosely connected to said end pieces to permit a parallel movement there-

of, means to clamp the die-plate to one of said pieces, supports for said stand which permits of its universal adjustment, and a counter-balance for said stand mounted on one of the supports.

In testimony whereof I have hereunto signed my name in the presence of two subscribing witnesses.

PETER VANDERAUWERA.
